UNITED STATES PATENT OFFICE

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY

MACHINE FOR OPERATING UPON SHEET MATERIAL

Application filed February 21, 1929. Serial No. 341,764.

3 The invention relates to machines for operating upon sheet material and is herein illustrated as embodied in a machine for stamping rubber sole stock, although it will be recognized that novel features of the invention are not limited to embodiment in machines of that type.

4 In performing various operations, for example stamping operations, upon certain kinds of sheet material, such as sheet rubber in the production of rubber soles and other articles, considerable difficulty has heretofore been experienced in automatically feeding sheets of material, or different portions of the 15 same sheet of material, accurately with relation to devices for operating upon the material. This difficulty has been found to be due largely to the flexibility of the material which causes it to stretch or buckle as it is moved 20 from one place of operation to another, thus making it difficult to feed it a definite distance without distortion.

5 In view of this, it is an object of the present invention to provide improved means for facilitating the handling and feeding of sheet material in a machine of the type referred to in order to render the operations performed upon the material more accurate and certain 25 without decreasing the production of the machine.

35 A feature of the invention consists in a novel organization of continuously operating mechanism for advancing sheet material past an operating instrumentality together with means for intermittently interrupting the 40 advance of the material and for presenting a portion thereof to the operating instrumentality. As illustrated, the machine embodying this organization comprises an endless 45 conveyor for feeding sheets of material along a table which is operable in timed relation with respect to the conveyor to move through the plane of the conveyor to interrupt the advance of the sheets by simultaneously removing all of them from the conveyor. Preferably, mechanism is provided for controlling the advance of the sheets in spaced relation along the table so that each sheet as it reaches the operating station and is removed from 50 the conveyor will be positioned laterally in

predetermined relation with respect to the operating instrumentality.

5 In handling material in the manner above outlined, the sheets are not subjected to pressures which would tend to distort them in such way as to make their feeding uncertain, and the operation of the table is effective to present a sheet to the operating instrumentality only after it has been advanced by a predetermined distance. In this way successive operations can be performed upon the same sheet accurately and economically with respect to the use of material. Furthermore, the continuous operation of the conveyor reduces the time required for locating the material in operative position substantially to a minimum. The simultaneous removal of all of the material from the conveyor results in the preserving of the spaced relation of the sheets as they are advanced so that there is no interference between a sheet at the operating station and the preceding or succeeding sheets.

6 Another feature of the invention consists in the provision of improved means for successively locating different portions of a sheet of material with respect to the operating instrumentality so that several operations may be successively performed on the same sheet of material at predetermined intervals. The construction shown comprises a series of stops for locating different portions of the sheet of material relatively to the operating instrumentality in turn, the conveyor being operative to feed material from one stop to another between operations upon the material.

7 Novel mechanism is also provided for arresting the advance of a sheet until the preceding sheet has passed the operating instrumentality.

8 The above and other features of the invention will now be more particularly described by reference to the accompanying drawings and pointed out in the claims.

9 In the drawings,

10 Fig. 1 is a perspective view of a machine embodying the invention;

11 Fig. 2 shows a portion of a sheet of mate-

rial upon which the machine is designed to operate;

Fig. 3 is a view, partly in section, transversely through the machine;

Fig. 4 is a side view of the operating instrumentality and conveyor mechanism;

Fig. 5 is a detail view showing stop mechanism; and

Figs. 6 and 7 are detail views showing the table-elevating mechanism.

As shown in Figs. 1 and 2, the illustrated machine comprises a horizontally disposed frame 10 supported upon standards 12. Centrally of the frame 10 is located a die 13 for performing a plurality of successive stamping operations upon each of a succession of sheets of material, such as rubber sole stock, advanced in turn past said die by means of a continuously operating endless conveyor 14. Normally positioned below the plane of the conveyor is a table or grid 16 constituting a work support which is arranged for intermittent movement vertically through the plane of the conveyor to remove each sheet of material from engagement with the conveyor and to support the material during each of the successive operations performed upon it.

The conveyor 14 comprises a drive chain 18 and a plurality of driven chains 20 extending in a horizontal direction and passing round sprockets 22 secured to shafts 24 rotatably mounted at opposite ends of the frame 10. The drive chain 18 passes over idler sprockets 26 (Fig. 3 and 4) and a drive sprocket 28 which is secured to a shaft 30 driven by a pulley 32, the arrangement being such that the chains 18 and 20 are continuously driven, during the operation of the machine, so that their upwardly disposed surfaces adjacent to the table 16 move lengthwise of the machine from right to left in Fig. 1. In order to prevent sagging of the chains between the shafts 24 a plurality of longitudinally extending grooved guides 34 (Fig. 3) are secured to the frame 10 in position to receive and support the chains.

To provide means for adjusting the tension on the chains, the shaft 24 at the left end 50 of the machine, as viewed in Fig. 1, is mounted upon a lever 36 pivoted to the frame 10 at 38 (Fig. 7). A bolt 40, which passes through the frame 10 and is threaded into a collar 42 pivoted on the lever 36, secures the lever in position. By turning the bolt 40 the lever can be moved about its pivot 38 in a direction to tighten or loosen the chains as required.

In feeding sheets of rubber sole stock by means of the conveyor it has been found desirable to make use of a cutting board, preferably made of rag stock, to act as a support and guide for a sheet as it passes through the machine. Accordingly, each sheet, such as sheet 43 (Figs. 2, 3 and 4),

is positioned upon a cutting board, such as board 44, the bead 45 of the material (Fig. 2) being located parallel to one edge of the board and spaced therefrom by a predetermined distance in order to locate the stock centrally of the machine, and the edge of the board serving as positioning means, as hereinafter described. Each of the successive sheets of rubber is held in position upon a cutting board by means of spring clamps 46, one of which is shown in Fig. 2. Each of the clamps 46 comprises a pair of pivoted members provided with gripper jaws 47 and handles 48, the jaws being normally urged toward each other by a spring, not shown. Two or more of such clamps are used in securing a sheet to a cutting board after alignment of the sheet with the board, the gripper jaws of the clamps being adjusted manually along one edge of the sheet and released so that the jaws grip between them the sheet and cutting board with the rubber sheet uppermost. In this way sheets are temporarily secured to and supported by the boards which can be fed by the conveyor predetermined distances without subjecting the sheets themselves to lateral pressures which would tend to distort the material.

To provide for moving the table or grid 16 vertically through the plane of the conveyor for removing the work comprising sheets carried by the cutting boards from the conveyor and supporting the work during operations performed upon it, the table 16 comprises a casting 49 from opposite sides of which project a plurality of rods 50, extending substantially the full length of the conveyor, secured to end members 52 and 53 (Figs. 1 and 6) carried by plungers 54 mounted for sliding movement vertically of the frame 10. The normal position of the table is in a plane parallel to but below the upper surface of the conveyor chains. Slots 55, best shown in Fig. 1, are provided in the casting 49 through which the chains 18 and 20 pass, so that the chains will not interfere with the movements of the table.

The table 16 is raised and lowered by means of bell-crank levers 56, best shown in Fig. 6, connected to the end members 52 and 53 by toggle links 58. The bell-cranks 56 are arranged for actuation by means of a cam 60 (Fig. 4) mounted upon a shaft 62 which is continuously driven by a link chain 64 from the shaft 30. The cam 60 is provided with a cam track 66 in which runs a roll 68 connected to a lever 70 mounted for oscillation about a pivot 72 on a frame member 73. Pivoted to the end of the lever 70 is a collar 74 slidably mounted upon link 76 which is connected to a lever 78 pivotally mounted on the frame 10. The link 76 is provided with a bushing 80 arranged for engagement with the collar 74 upon movement of the lever 70 in a counter-clockwise direc- 120 130

tion and by which the link 76 is moved upwardly. A spring 82 is positioned on the lower end of the link 76 between the collar 74 and a washer 84, the arrangement being such that movement of the lever 70 in a clockwise direction causes the collar 74 to compress the spring 82, thereby yieldingly to move the link 76 downwardly. Operation of the table responsive to movements of the link 76 is effected by rods 86 and 88 which connect the lever 78 with the bell-crank 56 at opposite ends of the machine, a spring 90 being provided to counterbalance the weight of the table 16.

16 The construction just described is such that the table 16 is moved up or down upon actuation of the lever 76 downwardly or upwardly by the cam 60. Thus the table is moved intermittently up and down through the plane 20 of the conveyor 10 in timed relation to the rotation of the cam.

The timing of the cam 60 is such that between elevations of the table the conveyor operates to feed a sheet, which has been advanced to the die 13, the proper distances for 25 successively locating different portions of the sheet relatively to the die 13 for performing a plurality of operations upon the sheet. Movement of the table into raised position 30 is effective to remove from the conveyor all of the sheets of material resting upon it, that is, sheets which have been advanced past the die, the sheet being operated upon, and the sheet or sheets which are to be advanced to 35 the die. When the table is lowered the sheets are returned to the conveyor for further feeding movement.

Means is provided for locating the forward end of each sheet of material as it is fed with 40 respect to the die and for subsequently determining the position of each sheet to locate different portions thereof relatively to the die. To this end use is made of a gage which 45 comprises a bar 94 (Figs. 1 and 4) pivotally and slidably mounted in brackets 96 and 98 on the frame and extending in the direction of feed of the material. Upon the bar 94 are 50 a plurality of raised projections 100 extending lengthwise thereof, each of said projections having a number of stops 102 pivotally 55 connected thereto. Each of the stops, which are preferably formed of sheet metal, has a tail piece 104 and a nose portion 106 substantially U-shaped in cross-section. Springs 60 108 are provided normally to hold the nose portions 106 extended outwardly from the 65 projections 100 but the construction is such that a stop may be rotated, in a manner to be explained, about its pivot until its nose portion projects only slightly from the surface of a projection 100, the lower part of the nose portion being received in a slot 110 in the projection. The number of stops may be varied as desired to control the spacing of 70 operations upon sheets of various sizes. The

stops are spaced along the gage according to the distance it is desirable to feed the work between operations performed upon it, the gage in the present instance being provided with four sets of stops by which several different spacings can be obtained, it being necessary only to rotate the gage upon the bearings in brackets 96 and 98 until the desired series of stops is uppermost. As shown in Fig. 4, only the stops in uppermost position are operative at any given time. In this position the stops project slightly above the plane of the conveyor 14 into the path of advance of the work so that, as the work is advanced against the stops by the conveyor, 75

80 feeding movement of the sheet is arrested. It should be noted that each sheet of material is positioned upon a cutting board with its forward edge slightly to the rear of the corresponding edge of the board so that the stops contact with the edge of the board rather than with that of the sheet thus to eliminate likelihood of curling the edge of the sheet. The gage 94 is capable of a slight movement longitudinally of the line of feed, said gage normally being held to the right, as viewed in Fig. 4, and in contact with the bracket 96, by means of a spring 111 positioned between bracket 98 and a flange 113 on the gage.

85 After the forward end of the work contacts with the first stop (102) the gage is moved by the work a slight distance to the left until further movement of the bar 94 and stop is prevented by a bracket 98. The stop then

90 arrests further advancing movement of the work which is now properly located laterally for the operation of the die. As the table is operated to elevate the work into position to be operated upon, the work is raised above the nose portion 106 of the stop with which it is engaged, releasing the gage 94 which is moved to the right by the spring above referred to. This movement brings the first stop underneath the edge of the work so that 95 when the table is lowered, returning the work to the conveyor, the forward edge thereof meets with no resistance until it has advanced into engagement with the second stop after which the cycle is repeated. The

100 weight of the work is sufficient to depress the springs 108, moving the stops about their pivots until their nose portions 106 are close to the projection 100, thus enabling the work to rest substantially flat upon the conveyor. 105

110 For effecting proper location of the work transversely of the die 13, the machine is provided with means comprising a gage plate 112 (Fig. 1) secured to the table and extending in a vertical direction along one side thereof. Periodically actuated devices operate to move the aligned side edges of the sheets and cutting board into engagement with the gage plate to position them. To this end, as shown in Figs. 1 and 2, a pusher rod 114 is arranged 115 to contact with the clamps 46 and to move 120

79

75

100

105

110

115

120

125

130

them and the work to which they are clamped transversely of the conveyor and table. The pusher rod 114 is carried by arms 116 connected by links 118 to a rod 120 secured to brackets 122 and 124 extending from the table 16. A shaft 126 rotatably mounted in said brackets is connected to the arms 118 by means of links 128 and 130.

Mounted on the side of the machine frame is a shaft 132 operatively connected to the shaft 126 by lever 134 and links 136 and 138. A spring 140 is provided tending normally to turn the shaft 132 in such manner as to effect a rocking of the shaft 126 in a direction to move the pusher 114 inwardly, thus effecting a yielding pressure upon clamps 46 to force them and the work held by them toward the gage 112. The timing of this movement is controlled by a cam face 142 (Fig. 4) associated with the cam 60, which operates a plunger 144 (Figs. 1, 2 and 4) carried by the lever 146 and operatively connected by links 148 and 150 to shaft 132. When the high part of the cam face 142 engages the plunger 144, the latter is rotated against the force of the spring 140 to effect a retraction of the pusher 114. The construction and arrangement are such that the pusher 114 is moved inwardly yieldingly to press the work against the gage plate 112 as the work is advanced toward the die by the conveyor between elevations of the table, thereby insuring proper location of the material transversely of the operating devices prior to an operation thereon.

35 A guide rod 152, one end of which is pivotally secured to the pusher rod 114 and the other end being held by a bracket 154, serves as a guide for directing the clamps 46 into positions in which the clamps straddle the pusher, as shown in Fig. 2. The operator, in placing a cutting board with a sheet of material clamped thereto upon the conveyor, merely slides the work in a direction to bring the handles 48 of the clamps 46 over the guide rod 152, the clamps being guided thereby, automatically, onto the pusher rod 114 as the conveyor advances the work.

Means is provided for successively arresting the advance of sheets of material at a predetermined distance from the die 13 and for releasing them at the proper times so that each of them can be fed into operative position during a single advance movement of the conveyor between successive operations of the table.

To this end, a bracket 156 (Figs. 4 and 5) is secured to two of the rods 50 forming the table 16. Pivotal mounted in the bracket 156 is a member 158 which carries at one end a pair of stop fingers 160 and at the other end an arm 162 the purpose of which will be hereinafter explained. The fingers 160 are normally urged in a clockwise direction by means of a spring 164 (Fig. 5) which acts upon one end of the arm 162, movement of the fingers

in that direction being limited by set screw 166 arranged for contact with the arm 162.

When rotated in a clockwise direction the fingers 160 project above the plane of the conveyor 14, as shown in Fig. 4, into the path of the material in such manner as to engage forward edges of the cutting board thereby to arrest the advance of the work. This is for the purpose of preventing forward movement of a sheet until the preceding sheet has passed the die 13.

75 In order to release the stock from the retaining action of the fingers 160 at the proper time, use is made of a detecting mechanism which initiates operation of mechanism for rotating the fingers into inoperative position. The detecting mechanism comprises a detector plate 168 carried by a rod 170 slidably mounted in the frame 10, a spring 172 tending to force the rod and plate downwardly. 80 The rod 170 has a collar 174 having a groove 176 in which is positioned one end of a bell-crank lever 178 pivoted on a stud 179 carried by the frame. The other arm of the lever 178 is pivotally connected to a link 180 received loosely in a collar 181 fixed to the lower end of a lever 182 which is mounted upon a stud 184 for oscillating movement under the end of the arm 162. Normally the collar 181 is yieldingly held against a stop 85 190 (Fig. 4) on the link 180 by means of a spring 192.

90 Movement of the detector plate 168 downwardly is limited by means of set screw 193, carried by arm 194 secured to rod 170, which engages the frame 10 when the table is lowered, so that plate 168 does not extend into the path of feed of the work. However, when work is positioned upon the conveyor and the table is elevated, the detector plate is 95

100 raised slightly against the action of the spring 172 by the material positioned adjacent to the operating station, as shown in Fig. 4, the material actuating the lever 178 to move the link 180 to the left. In this position of the link 180 the upper arm of the lever 182 extends to the right out of engagement with the arm 162 so that the fingers 160 are rotated by spring 164 into elevated position slightly above the plane of the conveyor 110 thus to engage with the forward edge of stock which has been fed toward the operating station. During successive movements of the table the first sheet of stock is fed underneath the plate 168 until it has been advanced 115 beyond the plate, the fingers 160 meanwhile preventing forward movement of the second sheet.

120 After the rear end of the first sheet is advanced beyond the plate 168, the rod 170 is lowered under the action of spring 172, causing rotation of the lever 178 in a counter-clockwise direction and moving the link 180 to the right, as viewed in Fig. 5, with the result that the lever arm 182 is brought under 125

the arm 162. When the table next descends, the engagement of the arm 182 with the arm 162 results in counter-clockwise rotation of the member 158 and the fingers 160 are moved into inoperative position below the plane of the conveyor. The second sheet is then advanced underneath the plate 168 until it is brought to rest by the stop 102, and the cycle is repeated. A guard or locking member 195 (Figs. 4 and 5) secured to bracket 156 is provided to prevent movement of the arm 182 in directions either to engage or release the arm 162 except at such times as the table is in its elevated position. Thus, the advance and arrest of the sheets are in timed relation to the movements of the table.

As illustrated, the means for operating upon the work comprises means for impressing upon sheet rubber medallion stamps, such as those indicated by reference character S (Fig. 2). To this end, the die 13 (Figs. 3 and 4) carried by a fixed head (not shown) is so positioned above the casting 49 as to be slightly spaced therefrom when the table 16 is in its uppermost position. Slidably mounted in an extension 196 of the casting 49 is a plunger 198 arranged for movement toward and away from the die 13 for pressing material in operative position against the die, thereby to impress medallion stamps upon the material. The plunger 198 is operated intermittently by means of toggle mechanism comprising links 200 and 202 which are actuated by a link 204 connected to the cam-operated lever 70. The link 200 is connected to the lower end of the plunger 198, and the link 202 is pivotally connected to a forked lever 206. The lever 206 is supported near the link 202 by a threaded shaft 208 extending into the frame member 73 and through a pivot pin 210 carried by the fork of the lever. The other end of the lever 206 is provided with a curved extension which is positioned in a slot 212 in a plunger 214 mounted in a frame member 216. A heavy spring 218 located within the frame member 216 tends to rotate the lever 206 in a clockwise direction against the thrust of the toggle link 202 when the toggle is straightened, thereby yieldingly to take the thrust of the toggle. Rotation of the shaft 208, effected by a hand-wheel 220 (Fig. 3) on shaft 222 carried by the frame, through bevel gears 224 on shaft 222 and 226 on shaft 208, raises or lowers the forked end of the lever 206 substantially about the center of the extension 211, the lever 206 being sufficiently long so that there is very little movement at its outer end. Adjustment of the forked end of the lever 206 up or down raises or lowers the lower pivot point of link 202 so that when the toggle is straightened the plunger will terminate its upward movement higher or lower with respect to die 13. This adjustment is provided to take care of operations

upon different thicknesses of material. Since the spring 218 exerts substantially the same pressure upon the plunger 214 against forces tending to straighten the toggle, the stamping pressure will remain substantially the same for any adjustment of the plunger operation for any thickness of material.

Mechanism is provided for releasing the spring clamps 46 from the cutting boards and sheets carried thereby after they have passed the operating station. This mechanism comprises two rods 228 (Figs. 1 and 3) carried by links 230 secured to shafts 232 supported in brackets 234. The links 230 are provided with intermeshing racks 236 which insure movement of the links 230 in unison about the shafts 232. To one end of the lowermost link 230 is connected an actuating rod 238 which is operable by means of a foot treadle 240 through a series of connections comprising a bell-crank 242, a rod 244, a bell-crank 246 and a rod 248. By depressing the treadle 240 the rod 238 is lowered, causing links 230 and rods 228 to rotate toward each other. As rods 228 approach each other they contact with the handles 48 of the spring clamps 46 in such manner as to open the jaws 47 of the clamps, releasing them from the material. A spring 250 surrounding connection 244 operates to return the rods 228 to inoperative position after the treadle 240 is released.

In order to provide for the return of the released clamps to the end of the machine where they can be used for positioning and guiding fresh sheets of material on the conveyor, the machine is provided with a belt 252 (Figs. 1 and 3) passing over roller 254 and shaft 256 which is driven by pinion 258 operatively connected to shaft 24. The belt is driven in the direction to carry the clamps, which fall thereon when released, to the right-hand end of the machine (Fig. 1). By this device the operator who supplies the sheet material to the machine is relieved of the necessity of leaving his station to obtain clamps.

Preparatory to operation of the machine, sheet material such as sheets of rubber are temporarily secured to cutting boards by means of clamps such as clamps 46 (Fig. 2) in the manner above described. An operator who is supplied with a number of such sheets secured to cutting boards stands at the right-hand end of the machine (Fig. 1) and places the work, one piece at a time, upon the conveyor 14 with the arms of the clamps in engagement with the guide rod 152. The material is then advanced toward the die by the conveyor, the pusher rod 114 being moved inwardly yieldingly to press against the clamps and to move the work secured thereto against the gage plate 112 thereby to locate the work transversely of the machine. The first piece

of work is advanced by the conveyor until its forward edge engages with the first of the stops 102 which arrests movement of the work. The table 16 is then elevated to remove the work from the conveyor and to present it to the die 13 which performs a stamping operation thereon. While the work is being operated upon, the first stop 102 is moved to the right underneath the edge of the work so that when the table is lowered upon the completion of the stamping operation, returning the work to the conveyor, the first stop is rendered inoperative and the conveyor is effective to feed the work to the next stop. The work is thus advanced from one stop to another in succession and operations are performed upon it between the feeding movements until the work has been advanced past the die. An operator then depresses the treadle 240 (Fig. 2) to effect engagement of the rods 228 with the handles of the clamps thereby to release the clamps from the work which is then removed from the conveyor. The released clamps fall upon the belt 252 which carries them back to the right-hand end of the machine where they can again be used in securing sheets to cutting boards.

As the first piece of work is being advanced a second piece is placed upon the conveyor but its advance movement is arrested by the stop fingers 160 which are rotated into the path of feed of the second sheet in response to movement of detector plate 168 which is actuated upon engagement with the first sheet when the table is elevated. The second piece of work is held against advance movement by the stop fingers 160 until operations upon the first piece of work has been completed after which the fingers 160 are depressed and the second piece of work advanced into engagement with the stops 102 and the cycle of operations is repeated.

Having described my invention, what I claim as new and desire to secure by Letters Patent of the United States is:—

1. In a machine for operating upon flexible sheet material, a conveyor adapted to feed sheet material, means for operating the conveyor uninterruptedly, a work support normally below and spaced from said conveyor, above and across which sheet material is fed by the conveyor, and means operative intermittently to elevate the work support into engagement with material fed by the conveyor and to cause the work support to lift said material from the conveyor, thereby interrupting the feeding of the material.

2. In a machine for operating upon flexible sheet material a conveyor adapted to feed sheet material, means for operating the conveyor uninterruptedly, a work support normally spaced from the conveyor, above and across which sheet material is fed by the con-

veyor, and means operative intermittently to move the work support into engagement with material fed by the conveyor and to cause the work support to remove said material from the conveyor, thereby interrupting the feeding of the material.

3. In a machine for operating upon flexible sheet material, a conveyor adapted to feed sheet material, means for operating the conveyor uninterruptedly, a work support normally spaced from the conveyor, above and across which sheet material is fed by the conveyor, and means operative intermittently to cause relative movement of the conveyor and work support to effect engagement of the work support with the material fed by the conveyor and to cause the work support to remove said material from the conveyor thereby interrupting the feeding of the material.

4. In a machine for operating upon flexible sheet material, an operating instrumentality, a conveyor adapted to feed sheet material, means for operating the conveyor uninterruptedly, a work support normally spaced from said conveyor, above and across which sheet material is fed by the conveyor, and means operative intermittently to cause relative movement of the conveyor and work support to effect engagement of the work support with the material fed by the conveyor and to cause the work support to remove the material from the conveyor to present the material and to support it for operation by the operating instrumentality.

5. In a machine for operating upon flexible sheet material, an operating instrumentality, continuously operating means for feeding the material past the operating instrumentality, and means movable relatively to the feeding means to remove the material therefrom and to support the material in fixed position during operations performed upon it.

6. In a machine for operating upon flexible sheet material, an operating instrumentality, means for feeding a sheet of material past the operating instrumentality, means for operating said feeding means uninterruptedly, and means operative to remove the sheet from the feeding means and to present it to the operating instrumentality.

7. In a machine for operating upon sheet material, an operating instrumentality, a continuously operating conveyor for feeding sheets of material past said instrumentality, means for controlling the spacing of the sheets being fed, and means for simultaneously removing all of the sheets from the conveyor and for presenting one of them to said instrumentality.

8. In a machine for operating upon sheet material, an operating instrumentality, a table movable into and out of position for supporting the material to be operated upon in operative relation to said instrumentality,

and continuously operating means for feeding the material above and across the table, the construction and arrangement being such as to effect a release of the material from the feeding means upon movement of the table toward said instrumentality.

9. In a machine for operating upon sheet material, a continuously operable endless conveyor for feeding sheets of material from one end of the machine toward the other, a table normally positioned below the plane of the conveyor and extending substantially the entire length of the conveyor, intermittently operable means for elevating the table through the plane of the conveyor thereby to raise the sheets out of engagement with the conveyor, and means for operating upon one of the sheets while it is in raised position.

10. In a machine for operating upon sheet material, a continuously operating endless conveyor for feeding sheet material in a horizontal direction, a table normally positioned below the conveyor and extending substantially the entire length thereof, intermittently operable means for elevating the table through the plane of the conveyor thereby to raise the material out of engagement with the conveyor, and means for performing operations upon a portion of the material while it is in raised position.

11. In a machine for operating upon sheet material, a continuously operating endless conveyor for advancing said material, a table normally positioned below the plane of feed of sheet material supported upon the conveyor, and means intermittently operative for moving the table through said plane of feed to remove the material from the conveyor.

12. In a machine for operating upon sheet material, a table extending lengthwise of the machine, means for feeding sheet material above and across said table from one end thereof toward the other, and means for moving the table to remove the material from the feeding means.

13. In a machine for operating upon sheet material, a work support extending lengthwise of the machine, means for feeding sheet material above and across said work support from one end thereof toward the other, and means for relatively moving the feeding means and the work support to cause the work support to engage with and to remove the material from the feeding means.

14. In a machine for operating upon sheet material, an instrumentality for effecting operations upon sheet material, a table normally located below the plane of operations upon the material, feeding devices positioned above the table in its normal position and operative to feed sheets of material past the instrumentality, and means operative intermittently to elevate the table above the feeding means and to hold the sheets in fixed position during operations performed upon one of them.

15. In a machine for operating upon sheet material, an endless conveyor for sheet material, a table normally positioned below the plane of the conveyor, intermittently operable means constructed and arranged for moving the table through the plane of the conveyor to remove the material therefrom, and means for operating upon the material while it is out of engagement with the conveyor.

16. In a machine for operating upon sheet material, an operating instrumentality, a continuously operating conveyor for advancing sheet material past said instrumentality, and means for removing the material from the conveyor when the material has been advanced into position to be operated upon and for supporting it in operative relation to the instrumentality.

17. In a machine for operating upon sheet material, an operating instrumentality, a continuously operating conveyor for feeding material past said instrumentality, means for arresting feeding movement of the material when it has been advanced into operative position laterally of the instrumentality, a work support, and means for effecting relative movement of the conveyor and work support to remove the material from the conveyor and to hold it in position for operation thereon by said instrumentality.

18. In a machine for operating upon sheet material, an instrumentality for operating upon sheet material, a continuously operating conveyor for feeding the material past said instrumentality, means for arresting feeding movement of the material when it has been advanced into a predetermined position relative to said instrumentality, and means operable through the plane of the conveyor to remove the material from the conveyor and to hold it in fixed position during an operation performed by said instrumentality.

19. In a machine for operating upon sheet material, an operating instrumentality, a continuously operating conveyor for advancing a sheet of material past said instrumentality, means for successively arresting the advance of the sheet with the forward end thereof in predetermined positions relatively to the instrumentality, and means for removing the sheet from the conveyor and for presenting it to the instrumentality between successive operations of the arresting means.

20. In a machine for operating upon sheet material, a continuously operating conveyor for successively advancing sheet material from one end of the machine toward the other, means for operating upon the material, means for intermittently arresting the advance of the material to locate different portions of it laterally with respect to the operating means, and means for removing the

material from the conveyor to present it to said operating means and for returning the material to the conveyor after an operation has been performed thereon.

5 21. In a machine for operating upon sheet material, an operating instrumentality, means for feeding a sheet of material past said instrumentality, means for operating said feeding means uninterruptedly, means for successively arresting the advance of the sheet being fed by the feeding means as the sheet successively reaches predetermined positions relatively to said instrumentality, and means operative intermittently to remove the sheet of material from the feeding means and to present successive portions of the sheet to the operating instrumentality.

10 22. In a machine for operating upon sheet material, an operating instrumentality, a continuously operating conveyor for feeding the material past the instrumentality, and means operating through the plane of the conveyor for alternately removing the material from and replacing it in engagement 25 with the conveyor thereby to present different portions of the material to said instrumentality.

30 23. In a machine for operating upon sheet material, an operating instrumentality, means for feeding a sheet of material past said instrumentality, means for operating said feeding means uninterruptedly, and means operative intermittently to remove the sheet of material from the feeding means and 35 to present successive portions of the sheet to the operating instrumentality.

40 24. In a machine for operating upon sheet material, an operating instrumentality, a continuously operating conveyor for feeding sheets of material in turn past said instrumentality, means positioned in the path of feed of the sheets for locating successively the forward ends of the sheets relatively to the operating instrumentality, and means for 45 moving a sheet from the conveyor into position to be operated upon by said instrumentality.

50 25. In a machine for operating upon sheet material, an operating instrumentality, means for feeding sheets of material past said instrumentality, means for successively locating each sheet in turn in operative position laterally of the operating means, and means for moving the sheets from the feeding 55 means into the plane of operation of said instrumentality.

60 26. In a machine for operating upon sheet material, an operating instrumentality, a continuously operating conveyor for feeding sheets of material successively past said instrumentality, a stop normally positioned in the line of feed of the sheets for locating successively the forward ends of the sheets relatively to the operating means, means for moving 65 a sheet from the conveyor into position

to be operated upon by the instrumentality and for returning it to the conveyor after an operation has been performed thereon, and means for moving the stop in a direction opposite to the feeding movement while the sheet is disengaged from the conveyor thereby to render the stop inoperative.

70 27. In a machine for operating upon sheet material, a work support, a continuously operating conveyor for advancing sheet material above and across the work support, a member normally disposed in the path of movement of the material for arresting the advance thereof, means for causing relative movement of the work support and conveyor 80 to remove the material from the conveyor and to return the material to the conveyor, and means for rendering the member inoperative for further arresting the advance of the material.

85 28. In a machine for operating upon sheet material, a work support, a continuously operating conveyor for advancing sheet material above and across the work support, a yieldable stop disposed in the path of movement of the material for arresting the advance thereof, means for causing relative movement of the work support and conveyor to remove the material from the conveyor and to return it to the conveyor, and means operable while the material is removed from the conveyor for moving the stop in a direction opposed to the direction of advance of the material to render the stop inoperative.

90 29. In a machine for operating upon sheet material, means for feeding sheet material, means for arresting the feed of the material in predetermined positions comprising a plurality of stops normally extending into the path of feed of the material, means for moving the material out of engagement with the stops, and means for moving the stops in the path of feed of the material while the material is disengaged therefrom for effecting advance of the material from one stop to another.

95 30. In a machine for operating upon sheet material, means for feeding the material, a plurality of stops normally extending into the path of feed of the material and mounted 105 for movement out of the path of feed, means for advancing the material successively from one stop to another, means for moving the material out of and back into the path of feed, and means for rendering one of the stops inoperative upon return of the material into the path of feed.

110 31. In a machine for operating upon sheet material, a continuously operating conveyor 115 for feeding sheet material, a series of pivotally mounted stops normally extending into the path of feed of the material for successively arresting the advance of the material, and means co-operating with the feeding 120

means for advancing the material from one stop to another.

32. In a machine for operating upon sheet material, an operating instrumentality, means for feeding sheet material past said instrumentality, and a gage comprising a rotatably mounted bar and a plurality of series of spaced stops carried by the bar, the construction and arrangement being such that each of the series of stops can be positioned selectively in the path of feed of the material.

33. In a machine for operating upon sheet material, an operating instrumentality, a continuously operating conveyor for advancing sheets of material past said instrumentality, a detector plate for determining the presence of a sheet in proximity to the instrumentality, a stop finger, and means responsive to operations of the detector plate for moving the stop finger into and out of the path of advance of the sheets.

34. In a machine for operating upon sheet material, an operating instrumentality, a continuously operating conveyor for advancing sheets of material past said instrumentality, means for determining the presence of a sheet of material in proximity to said instrumentality, a stop finger, and means for moving the stop finger into the path of advance of the material when a sheet is located in proximity to the instrumentality in order to arrest the advance of a succeeding sheet of material.

35. In a machine for operating upon sheet material, an operating instrumentality, a continuously operating conveyor for advancing sheets of material past said instrumentality, a stop finger, and means for moving the stop finger into the path of advance of the material operable when a sheet is located in proximity to the said instrumentality in order to arrest the advance of a succeeding sheet of material.

36. In a machine for operating upon sheet material, an operating instrumentality, a continuously operating conveyor for advancing sheets of material past said instrumentality, means for determining the presence of a sheet in proximity to the instrumentality, and means responsive to the first-mentioned means for arresting the advance of a succeeding sheet of material until an operation has been completed upon the first sheet.

37. In a machine for operating upon sheet material, an operating instrumentality, a continuously operating conveyor for advancing sheets of material past said instrumentality, means for removing a sheet from the conveyor and for presenting it to the instrumentality, a stop finger, and means for engaging with a sheet when it is presented to the instrumentality operable to effect movement of the stop finger into the path of movement of the material to arrest the advance of a succeeding sheet of material.

38. In a machine for operating upon sheet

material, an operating instrumentality, a conveyor for advancing sheets of material past the instrumentality, means for determining the presence of a sheet in proximity to the instrumentality, a member normally operable for arresting the advance of a sheet toward the instrumentality, and means responsive to the first-mentioned means for rendering said member inoperative.

39. In a machine for operating upon sheet material, an operating instrumentality, a continuously operating conveyor for advancing the material past the instrumentality, means operative intermittently to arrest the advancing movement of the material successively to locate it in different positions longitudinally of the operating means, and means for moving the material on the conveyor transversely of the operating means while the material is being fed.

40. In a machine for operating upon sheet material, an operating instrumentality, a continuously operating conveyor for advancing material past said instrumentality, intermittently operated means for removing the material from the conveyor thereby to interrupt the advance of the material, and means operable in timed relation to movements of the intermittently operated means for aligning the material transversely of the conveyor.

41. In a machine for operating upon sheet material, an operating instrumentality, a continuously operating conveyor for advancing material past said instrumentality, a gage mounted independently of the conveyor for locating the material transversely of the conveyor, and means operable intermittently yieldingly to move the material toward the gage as the material is being advanced.

42. In a machine for operating upon sheets of material which are temporarily secured to cutting boards by means of clamps, a continuously operating conveyor for advancing the material, and means for engaging the clamps to locate the material transversely of the conveyor.

43. In a machine for operating upon sheet material which is temporarily secured to a cutting board by means of clamps, a conveyor for advancing the material, and intermittently operated means constructed and arranged to engage the clamps and to move the clamps and the material transversely of the conveyor.

44. In a machine for operating upon sheet material which is temporarily secured to a cutting board by means of clamps, an operating instrumentality, a conveyor for advancing the material past the instrumentality, and means for releasing the clamps from the material.

45. In a machine for operating upon sheet material which is temporarily secured to a cutting board by means of clamps, means for advancing the material from one end of the

machine toward the other, means for releasing the clamps from the material and cutting board, and means for returning the released clamps to the first-mentioned end of the machine.

5 46. In a machine for operating upon sheet material which is temporarily secured to a cutting board by clamps, a conveyor for feeding the material, and means constructed and arranged for engaging the clamps to guide the material as it is placed upon the conveyor.

10 47. In a machine for operating upon sheet material which is temporarily secured to a cutting board by clamps, means for feeding the material, a member constructed and ar-

15 ranged to engage the clamps for locating the material transversely of the machine, and means for guiding the clamps toward said member.

20 In testimony whereof I have signed my name to this specification.

ERASTUS E. WINKLEY.
